UNITED STATES PATENT OFFICE.

CHARLES VAN AMBURGH, OF TACOMA, WASHINGTON, ASSIGNOR TO AMERICAN SMELTING & REFINING CO., A CORPORATION OF NEW JERSEY.

PROCESS AND APPARATUS FOR REMOVING ACCRECTIONS FROM MECHANICAL TWYERS.

1,292,162.

Specification of Letters Patent.

Patented Jan. 21, 1919.

Application filed May 21, 1918. Serial No. 235,869.

To all whom it may concern:

Be it known that I, CHARLES VAN AMBURGH, a citizen of the United States, and resident of Tacoma, in the county of Pierce 5 and State of Washington, have invented certain new and useful Improvements in Processes and Apparatus for Removing Accretions from Mechanical Twyers, of which the following is a specification.

10 My invention relates to a process and apparatus for removing accretions from the discharge pipe of a mechanical twyer used for injecting various materials and gases into furnaces, converters, and the like.

15 It is well known that in many cases where mechanical twyers are used, the materials being treated in the furnace or converter gradually accumulate at the discharge end of the apparatus, due to various causes 20 which are well understood, and it is necessary from time to time to remove these accretions in order to maintain the maximum opening at the point of discharge.

For this purpose it has been customary 25 heretofore to provide a shaped rod or the like, which is pushed through the discharge pipe, and used as a scraper to remove the accretions. If this operation is performed while the apparatus is in use, there is a considerable loss of injector air during the 30 operation. Furthermore, to successfully accomplish the purpose, it is desirable that the rod should be almost as large in cross-sectional area as the internal area of the discharge opening, and it results from this that 35 while the rod is being withdrawn, there may not be sufficient air passing around it to prevent the molten material in the furnace or converter flowing back into the discharge pipe, and thus to a certain extent defeating the purpose of the cleansing operation.

The object of my invention is to remove 40 the accretions in the discharge pipe without interfering with the operation of the furnace or converter, without reducing the air blast thereto, and without opening the apparatus for any manual operation.

In the accompanying drawing I show one 45 form of apparatus for carrying this invention into effect, in which 1 is the wall of a converter, 2 is the discharge pipe of the twyer, 3 is the air connection, and 4 is the connection for the gas or material to be supplied to the converter.

50 In addition to the ordinary low pressure

air for blowing the converter and injecting the material, I provide a high pressure air connection 5 from an air supply tank, not shown. In the high pressure air line there is a quick acting valve 6, and at the point 60 where the high pressure air line joins the low pressure air line there is a check valve 7. A check valve 8 adjacent the opening 4 closes said opening against the air.

In order to remove the accretions it is only 65 necessary to open the quick acting valve 6, whereupon the high pressure air will close the check valve 7, and cut off the low pressure air supply. The high pressure air in passing through the discharge pipe of the 70 twyer will remove the accretions, and under ordinary conditions this result can be satisfactorily accomplished in a matter of seconds or at most a matter of a few minutes.

It will be observed that by this apparatus 75 the blowing of the converter is not interrupted, and that no manual operation is required other than the opening and closing of the quick acting valve.

The discharge end of the twyer is always 80 under air pressure, and choking of the twyer by inward flow of material following the withdrawal of the push rod is completely avoided. Not only may accumulations or accretions of material on the twyer be removed, but such accretions may be entirely 85 prevented by intermittently admitting air through the high pressure pipe. The pressure of the high pressure air usually is several times that of the low pressure air, but 90 both its volume and its pressure may be regulated according to the circumstances or the occasion of its use. The general arrangement of the parts of the apparatus heretofore employed is not materially modified, and in 95 case of emergency the twyer pipe can be cleared by a push rod or in any other well known method.

While I have shown and described, and 100 have pointed out in the annexed claims, certain novel features of my invention, it will be understood that various omissions, substitutions and changes in the form and details of the device illustrated and in its operation may be made by those skilled in the 105 art, without departing from the spirit of the invention.

Having described my invention, what I claim is:

1. In an apparatus of the class described, 110

the combination of a low pressure air line 5
communicating with a converter twyer, a
high pressure air line communicating with
said low pressure air line, a valve in the high
pressure air line, and means for closing off
the flow of air in the low pressure air line
when the valve in the high pressure air line
is open.

2. In an apparatus of the class described,
10 the combination of a low pressure air line
communicating with a converter twyer, a
high pressure air line communicating with
said low pressure air line, a valve in the high
pressure air line, and automatic means
15 for closing off the flow of air in the low
pressure air line when the valve in the high
pressure air line is open.

3. In an apparatus of the class described,
20 the combination of a low pressure air line
communicating with a converter twyer, a
high pressure air line communicating with
said low pressure air line, a valve in the high

pressure air line, and automatic means actuated
by the high pressure air for closing off
the flow of air in the low pressure air line 25
when the valve in the high pressure air line
is open.

4. The process of removing secretions on
the discharge pipe of a converter twyer
which consists in intermittently blowing 30
through said discharge pipe air at a higher
pressure than that used for ordinary injector
purposes.

5. The process of preventing accretions on
the discharge pipe of a converter twyer 35
which consists in blowing through the twyer
a predetermined volume of air at a pre-set
pressure, and intermittently increasing the
volume of air and the pressure of the air,
substantially as described. 40

Signed at Tacoma, in the county of Pierce,
and State of Washington, this 17th day of
April, A. D. 1918.

CHARLES VAN AMBURGH.
